THERMIONICALLY EMITTING DEVICE

Pao-Hsien Fang, Washington, D. C., assignor to Philco Corporation, Philadelphia, Pa., a corporation of Pennsylvania

Application September 20, 1956, Serial No. 611,070

7 Claims. (Cl. 313—337)

The present invention relates to devices for the thermionic emission of electrons, and particularly to an improved emitter suitable for use in vacuum tube devices and similar apparatus.

Many important electronic devices now known and widely-used rely for their successful operation upon the thermionic emission of electrons. Among the more common of such devices are the ordinary vacuum-tube diode and triode, as well as the cathode-ray and magnetron tube. In most of such devices the emitted electrons are attracted by a positively-biased element, and the emitter, because of its relative negative potential, is commonly referred to as a cathode. In such emitters, it is generally desirable that relatively low temperatures be capable of producing high emission current densities, thereby to minimize the deteriorating effects inherent in high temperature operation and to reduce the magnitude of the heating currents required. It is also highly desirable in many applications that the emissive properties of the cathode persist to a substantial degree over long periods of time, and that these properties be substantially uniform over the whole area of the emitter surface.

Among the known types of thermionic emitters are those of metals such as tungsten, in which substantial emission is obtained only at very high temperatures, e. g. 2,000° centigrade or more. Activated metal emitters such as the thoriated-tungsten cathode, and various types of boride cathodes are also known which produce substantial emission at somewhat lower temperatures, but still at temperatures which are undesirably high for many purposes. Perhaps the best previously-known cathode from the viewpoint of low-temperature emission has been the so-called oxide-coated cathode, which produces satisfactory emission at temperatures in the region of 700° C. Unfortunately the success of the operation of the oxide cathode is based on a delicate balance of the non-stoichiometric composition with a minute excess of the metallic component, which can be attained only through elaborate procedures of preparation and aging. Therefore the oxide cathode is often characterized by unduly short life, caused particularly by "poisoning" of the emissive coating by minute traces of contaminants. In addition it is fragile under electronic and ionic bombardment such as is encountered in magnetron operation.

There has therefore existed a need in the art for a thermionic emitter which would exhibit substantial emission at relatively low temperatures, which would be characterized by long life and stability of operation, and yet be simple to manufacture. In an attempt to meet these requirements, there has been developed still another type of cathode commonly known as the dispenser-type cathode, which generally has longer life but requires higher temperatures than the oxide-coated cathode. However, the dispenser-type cathode is relatively complex in structure and critical in constituency and arrangement, and is also often characterized by a lack of uniformity in the emission from various portions of the cathode surface.

2

Accordingly it is an object of my invention to provide a new and improved thermionic emitter.

Another object is to provide a thermionic emitter characterized by relatively high emission at relatively low temperatures.

A further object is to provide such an emitter which is also characterized by long operating life.

Still another object is to provide a new and improved thermionic cathode which is capable of producing relatively high emission at relatively low temperatures, is characterized by long life, and yet is simple in construction.

It is another object to provide an improved emitter of the above-described general type in which substantially uniform emission may be obtained from the entire cathode area.

The above objects are achieved by the provision of a thermionically-emissive element comprising a single-crystal of the chemical composition $BaTiO_3$ or $PbTiO_3$.

20 I have found that either of these materials, when heated to temperatures of about 700° to 800° centigrade, exhibits relatively strong emission of electrons from substantially all portions of its exposed surfaces. In addition, the emitter of my invention does not appear to be susceptible to "poisoning," or to be sensitive to ion bombardment, and is therefore also characterized by extremely long life.

30 The use of a single-crystalline body of these titanate materials, as opposed to a polycrystalline body containing a conglomerate mixture of minute crystals, has been found to be of great importance in obtaining the desired high emission, since the single-crystalline materials exhibit a degree of emission which is commonly about four orders of magnitude greater than that of the same materials in polycrystalline form. Furthermore, the single-crystalline nature of the material conduces to a high degree of uniformity of emission from various portions of the cathode surface.

35 While all of the theoretical considerations involved in the operation of this novel form of cathode have not yet been thoroughly explored, it has been confirmed that these titanate materials exhibit semiconductive properties at elevated temperatures of operation, a factor which appears to contribute to the above-mentioned relatively high emission. The extremely high dielectric constant of the material, and its ability to form dipole layers at the surfaces thereof, also appear to be significant in producing the desired operation.

40 Other objects and features of the invention will be more fully appreciated from a consideration of the following detailed description, taken in connection with the accompanying drawings, in which:

45 Figure 1 is an elevational view, partly in section, illustrating vacuum-tube diode device utilizing the novel thermionic emitter of the invention; and

50 Figure 2 is a graphical representation illustrating the degree of emission obtained from the emitter of the invention in one of its forms, in comparison to the emission produced by certain other cathodes of the prior art.

55 Referring now particularly to Figure 1, in which the several elements are not necessarily to the same scale, there is shown one of the forms of vacuum-tube diode which was fabricated in the course of evaluation of the thermionic emitter of the invention. It will be understood that while the device is a diode, the emitter of the invention is of general utility as a cathode, and for example may be utilized in triode devices, and particularly in cathode-ray tubes. In Figure 1 in the single-crystalline titanate emitter element 10 of $BaTiO_3$ or $PbTiO_3$ is positioned against the inner, bottom surface of a generally cylindrical, cup-shaped metallic member 12, so as to overlie a circular opening 14 provided in support mem-

ber 12 through which the desired emission occurs. Support member 12, in turn, is held in position by supporting wires 16 and 18, which may each be spot-welded to member 12 at one of their ends, the other ends of wires 16 and 18 passing through insulating base member 20, by way of suitable glass-to-metal seals, to connecting pins 22 and 24.

The apparatus utilized in this instance to produce heating of emitter element 10 comprises a filament 30 located within a second metallic cup-like member 32 and having its two terminal leads connected to connecting pins 34 and 36. Member 32 is held pressed against the under-surface of emitter element 10 by means of the centrally-apertured ceramic disc 38 and the retaining member 40, which is of a suitable resilient metallic material spot-welded to member 12.

A metallic anode element 42 is mounted by pins 44 and 46 from a pair of glass supporting rods 48 and 50, which in turn are rigidly fixed to cup-shaped member 12 by pins 52 and 54. An appropriate connection 56 is also provided between anode 42 and the anode cap 58.

In the form of the device shown in Figure 1, a glass envelope 60 surrounds the operative elements just described and is evacuated in the manner usual for vacuum tubes so as to permit the free flow of electrons therein. Furthermore it will be understood that, in the course of assembly of the complete tube, care should be taken to insure a high degree of cleanliness and to avoid the introduction of harmful contaminants into the device.

In one specific form of the device shown in Figure 1, the emitter element was of BaTiO₃, the aperture 14 was one-eighth centimeter in diameter and the spacing between anode 42 and emitter element 10 was substantially one centimeter.

In normal use, a source of filament voltage is applied between connecting pins 34 and 36 to heat the emitter 10 to the required temperature and to permit preliminary aging thereof. The desired anode-cathode voltage is then applied between cap 58 and either or both of pins 22 and 24. When cap 58 is positive with respect to pins 22 and 24, electrons thermionically emitted by emitter 10 are attracted to anode 42 and flow through the connections and the external circuit in the usual manner. For the opposite polarity of applied potential, little or no current flows.

As mentioned hereinbefore, thermionic emitter 10 is a single-crystal of BaTiO₃ or PbTiO₃. Methods for producing single-crystals of such materials are well known in the art, and hence need not be described here in detail. For example, for a detail description of one method of fabricating such single-crystals, reference may be had to U. S. Patent No. 2,736,659, of L. E. Lynd and L. Merker, issued February 28, 1956.

Referring now to Figure 2, the emission obtained from a BaTiO₃ single-crystal in accordance with the invention is shown in comparison with that of several other known thermionic emitters. In the figure, ordinates represent the saturation emission densities for the several types of emitters, in amperes per square centimeter of surface, plotted to a logarithmic scale, while abscissae represent the temperature of the emitter in degrees centigrade. Curve A represents the emission for a tungsten cathode, curve B represents that for a thoriated tungsten cathode, curve C shows the emission for an emitter composed of lanthanum hexaboride, while curve D represents the emission obtained with the barium titanate cathode element of the invention. The curves A, B, C were obtained by

the well-known method in which a pulsed saturation voltage is applied between anode and cathode. The curve D was obtained by applying a D.-C. anode-cathode voltage of 500 volts, with an anode-cathode spacing of 1 cm., and by measuring the cathode current produced at various temperatures. From this graph it will be apparent that, while an emission current of about 0.1 ampere per square centimeter is obtained with the barium titanate cathode at about 940° C., this same current density is obtained only at substantially higher temperatures with the tungsten, thoriated tungsten and lanthanum hexaboride cathodes. More particularly, this current density is obtained in the case of tungsten at about 2100° C., in the case of thoriated-tungsten at about 1400° C., and, in the case of the boride emitter, at about 1250° C.

Single-crystal of PbTiO₃ have been found to possess substantially the same advantages in thermionic emission as the barium titanate emitter described hereinabove, and may be employed in the same structures mentioned with reference to possible applications of the barium titanate emitter. These advantages include not only the relatively high emission obtained at relatively low temperatures, but also the long life, uniformity of emission and simplicity of structure characterizing the barium titanate form of the invention.

While the invention has been described with particular reference to specific embodiments thereof, it may also be embodied in any of a variety of widely diverse forms, such as will occur to those skilled in the art in view of the foregoing description. Accordingly, the scope of the invention is limited only by the appended claims.

I claim:

1. As a thermionic emitter, a heated body of single-crystalline, material selected from the group consisting of barium metatitanate and lead metatitanate, and an evacuated chamber providing an evacuated region adjacent said body.

2. As a thermionic emitter, a heated, single-crystalline body of BaTiO₃ and an evacuated chamber providing an evacuated region adjacent said body.

3. As a thermionic emitter, a heated, single-crystalline body of PbTiO₃ and an evacuated chamber providing an evacuated region adjacent said body.

4. Apparatus for producing thermionic emission of electrons, comprising a single-crystalline body of a material selected from the group consisting of BaTiO₃ and PbTiO₃, an evacuated chamber providing an evacuated region adjacent said body, and means for heating said body to an elevated temperature, thereby to produce thermionic emission therefrom.

5. Apparatus in accordance with claim 4, in which said body is of BaTiO₃.

6. Apparatus in accordance with claim 4, in which said body is of PbTiO₃.

7. A vacuum-tube device, comprising a cathode of a single-crystalline material selected from the group consisting of BaTiO₃ and PbTiO₃, and an anode element contained in a common evacuated chamber with said cathode and electrically insulated therefrom.
